U.S. PATENT DOCUMENTS

D59,314 S	10/1921	Winsen
D63,931 S	2/1924	Bowden
D110,995 S	8/1938	Bellem, Jr.
D127,734 S	6/1941	Dreyfuss
D254,265 S	2/1980	Karamian
4,499,630 A	2/1985	Harris
D279,213 S	6/1985	Paul

FIG. 1 is a top, front, right perspective view of the claimed design;

FIG. 2 is a right side elevation view thereof;

FIG. 3 is a left side elevation view thereof;

FIG. 4 is a front elevation view thereof;

FIG. 5 is a rear elevation view thereof;

FIG. 6 is a top plan view thereof; and,

FIG. 7 is a bottom plan view thereof.

The ornamental design which is claimed is shown in solid lines in the drawings. The broken lines in the drawings are for illustrative purposes only and form no part of the claimed design. Broken lines formed by equal length dashes show unclaimed subject matter. Broken lines formed by unequal length dashes (i.e., dash-dot) define bounds of the claimed design.1 Claim, 5 Drawing Sheets| (56)	References Cited
